[57] CLAIM

The ornamental design for a fish shaped medallion, as shown.

DESCRIPTION

FIG. 1 is a plan view of a fish shaped medallion showing my new design;

FIG. 2 is a top view thereof as viewed in FIG. 1;

FIG. 3 is a bottom view thereof;

FIG. 4 is a left side view thereof as viewed in FIG. 1; and,
FIG. 5 is a right side view thereof.

The coin shown in broken lines in FIG. 1 denotes the nature and environmental use of the design and is not part of the design.
